UNITED STATES PATENT OFFICE.

ROBERT D. PARKS, OF LOHRVILLE, IOWA, ASSIGNOR TO W-M-P MANUFACTURING CO.,
OF LOHRVILLE, IOWA, A CORPORATION OF IOWA.

CORN POPPER.

Application filed February 3, 1919. Serial No. 274,688.

To all whom it may concern:

Be it known that I, ROBERT D. PARKS, a citizen of the United States, residing at Lohrville, in the county of Calhoun and

5 State of Iowa, have invented a new and useful Corn Popper, of which the following is a specification.

This invention has reference to corn poppers of the portable cabinet type, the object 10 of the invention being to provide a corn popper so constructed that it may be readily moved from place to place by an operator, and while being so moved the various instrumentalities employed in the corn-popping 15 operation may be housed within the cabinet in compacted condition.

The invention comprises a cabinet mounted upon wheels and provided with legs which, in conjunction with the wheels, constitute the supporting means for the cabinet, 20 permitting the cabinet to be pushed from place to place and facilitating the use of the cabinet on the streets or other like localities for the production and sale of popped corn.

The invention contemplates the use, in connection with the cabinet, of a hinged work-table having a railing, and foldable onto the top of the body of the cabinet, with 30 the railing dropping thereinto, and a popping kettle for the corn, accompanying the cabinet stored therein so that the whole apparatus when ready for transportation has all the parts thoroughly housed.

35 The invention contemplates the employment of handles which may be pulled out or pushed in, and when pulled out serve both as means whereby the cabinet may be propelled and as a support for the hinged top or table when extended.

40 The invention also contemplates an arrangement of a corn pan permitting it to receive and hold the popping kettle when the latter is not in use, to allow compacting 45 the various instrumentalities for transportation.

45 The invention will be best understood from a consideration of the following detailed description taken in connection with 50 the accompanying drawings forming part of this specification, with the understanding, however, that the invention is not confined to any strict conformity with the showing of the drawings, but may be changed and modified so long as such changes and

modifications mark no material departure from the salient features of the invention as expressed in the appended claims.

In the drawings:

Figure 1 is a perspective view of the cabinet showing the cover and other parts in the extended position and a wind-shield for the kettle also in position, the kettle itself being removed.

Figure 2 is a longitudinal vertical section 65 through the cabinet on the line 2—2, Figure 5 with the cover extended to constitute a shelf, and the kettle in place over the burner.

Figure 3 is a section similar to Figure 2 70 but showing the parts in the retracted position.

Figure 4 is a section on the line 4—4 of Figure 3.

Figure 5 is a plan view of the structure 75 shown in Figure 1 but with the kettle in place.

Figure 6 is a plan view of the structure shown in Figure 3 but with some parts in horizontal section.

Figure 7 is a detail section on the line 7—7 of Figure 3.

Figure 8 is a section on the line 8—8 of Figure 6.

Figure 9 is a fragmentary section showing 85 a portion of the propelling handle and adjacent parts.

Figure 10 is a section on the line 10—10 of Figure 9.

Referring to the drawings there is shown 90 a casing 1 which may be made of sheet metal with framing strips where needed, the casing constituting a cabinet for containing various parts of the corn popper.

The cabinet is supported upon wheels 2 95 at one end and at the other end is provided with legs 3. The wheels and legs form a support for the cabinet, the wheels 2 at one end permitting the ready propulsion of the cabinet from place to place, and the legs 100 3 at the other end preventing accidental displacement of the cabinet under ordinary working conditions.

Within the cabinet at the bottom there is lodged a tank 4 for fuel, and connected to 105 the tank is a filling plug 5, an air pump 6 and a pressure gage 7, and furthermore the tank is provided with a drain cock 8. Within the cabinet near one end is a burner jacket or casing 9 which may be of cylindrical form, 110

as shown, and provided with a series of air holes or perforations 10. Within the casing 9 there is located a burner 11 connected by a pipe 12 to the tank 4, said pipe extending 5 to near the bottom of the tank to utilize practically all of the fuel therein, which fuel may, if desired, be gasoline. The burner 11 is under the control of a valve provided with a hand wheel 13 for manipulation.

10 Within the casing 9 near the upper end there is located a ring 14 supported and spaced away from the inner wall of the casing by brackets 15. The brackets have inclined portions 16 to constitute a centering 15 support for a wind-shield 17, which latter has its circumferential continuity broken at one point, designated at 18, so that the wind-shield may be spread sufficiently to embrace the upper end of the casing 9 for storage 20 purposes, as shown in dotted lines in Figure 8.

The main body of the cabinet is provided with a cover 19 connected by hinges 20 to that end of the cabinet at the top thereof remote 25 from the portion in which the burner and parts associated therewith are located.

Entering that end of the casing remote from the burner are side bars 21 of a handle structure having a yoke portion 22 provided 30 with end legs 23 connected to the bars 21, the legs 23 and bars 21 where joining being in turn connected by a cross rod 24 forming with the bars 21 a rigid handle structure. The bars 21 slide through guide plates 25 35 and guide straps 26 within the cabinet and spaced apart lengthwise of the bars 21, so that the handle structure may be moved into and out of the cabinet with the yoke 22 movable close up against the corresponding wall of the cabinet or to an appropriate distance therefrom. Each bar 21 carries a bolt 27 in position to engage the corresponding plate 25 to limit the outward movement of the handle. (See Figure 10.) It will be understood, of course, that the bolt 27 may be replaced by any other appropriate stop means.

The inner end of each bar where passing through the strap 26, has in its path a pin 50 or screw 28, the strap being somewhat wider than the width of the bar so that by raising the outer end of the bar 21 and thereby tilting said bar, the inner end may be brought into abutment with the corresponding screw 55 28, thus, so long as the bar is so tilted, preventing the pushing of it into the cabinet, as shown in Figure 9.

The height of the yoke 22 is such as to 60 constitute a support for the top or table 19 when extended. The bars 21 are arranged on opposite sides of a portion of the interior of the cabinet shaped to receive a pan 29 designed to receive popcorn. This pan, which may be of generally rectangular shape and 65 slightly tapering toward the bottom, is open

at the top where it has a marginal outstanding flange 29^a and is of a height to hang from the top portion of the cabinet and reach close to a transverse floor or platform 30 above the tank 4 and below and supporting 70 the casing 9. (See Figure 3.) The pan 29 is covered by the top or table 19 when the latter is closed. Within the pan 29 is a screen partition 31 forming a false bottom, and the sides of the pan have matching 75 perforations 32 for the reception of rods 33 positioned to support the screen above the bottom of the pan whereby unpopped corn contained in the mass of popcorn sifts out therefrom and drops to the bottom of the 80 pan so that the popcorn is maintained clean. When it is desired to store the parts the screen 31 and rods 33 may be removed.

Below the portion of the cabinet containing the pan 29 there is located a drawer 34 85 movable into and out of the cabinet in the usual manner, and this drawer forms a convenient receptacle for the screen 31 and rods 33 when not in the pan 29. The drawer may also serve as a receptacle for various implements used in conjunction with the cabinet.

There is also provided a popping kettle 35 with exterior lugs 36 adapted to engage the ring 14 and support the kettle over the burner. The kettle is provided with a handle 37 whereby it may be manipulated and with stirring means, not shown, which may be actuated by a crank shaft 38, which shaft, when the kettle is in place over the burner, is readily accessible to an operator.

100 The kettle structure is not herein shown in detail, nor claimed, since it forms the subject matter of another application for Letters Patent, Serial Number 274,687, filed by me February 3, 1919. The pan 29 is provided near one corner with a recess 39 through which the handle 37 may extend, and a cover 39^a is provided for the recess 39 so that the latter may be closed when the pan is used for other purposes than storing 105 the kettle. This is for the purpose of storage, the kettle 35 being then placed within the pan 29, after the screen 31 has been removed and put in the drawer 34. (See Fig. 3.)

110 The handle 37 with the crank shaft 38 then extends through the recess 39 into the compartment containing the casing 9 surrounding the burner 11. (See Figure 6.) The windshield 17 is removed from within the casing 9 and expanded so as to be slipped over the upper end of the casing so as to be frictionally held in place and out of the way of other parts. The cover or table 19 is turned about its hinge connections 20 with the cabinet until in covering relation to the entire top of the cabinet. If it be desired to simply store the cabinet without moving it, the handle structure is pushed into the cabinet by depressing the yoke end, thereby lifting the bars 21 in such manner as to clear 115 120 125 130 135

the stop pins or screws 28. If, however, it be desired to move the cabinet to another place the handle member is allowed to remain in the projected position, and by lifting 5 on the handle member, thus bringing the inner ends of the bars 21 into abutment with the stops 28, the legs 3 may be lifted clear from the ground and the cabinet be propelled to any desired distance on the 10 wheels 2.

When it is desired to set the popping cabinet into operation after reaching the desired location, and assuming that the handle member is already pulled out from the cabinet 15 to the limit of its travel, the table or cover 19 is opened until it rests upon the yoke portion of the handle as indicated in Figures 1 and 2. The windshield 17 is removed from embracing relation to the casing 9 and then placed within the upper end 20 of the casing to rest on the portions 16 of the brackets 15. The kettle 35 is removed from the pan 29 and inserted in the ring 14 which engages the lug 36 on the kettle 25 thereby supporting the kettle over the burner. If there be no air pressure in the tank 4, a suitable pressure is established by means of the pump 6, such pressure being indicated on the dial of the pressure gage 7.

30 In operating the corn popper, a small quantity of grease is placed in the kettle, such grease consisting of lard or some lard substitute, and the kettle is set over the burner, which of course has been previously lighted. An appropriate quantity of unpopped corn, say about a cupful for a ten quart kettle, is poured into the kettle into the lard already melted therein. On actuating the stirrer, the unpopped corn 35 becomes thoroughly covered with the grease, which latter serves to harden or toughen the outer skin of the corn kernels so that the kernels will swell to a greater extent than usual, and when rupturing takes places, the kernels expand to a greater extent than customary, wherefore, there is produced a larger and more fluffy popped corn than is usual. Popcorn contains volatile oils which in the ordinary process of popping escape 40 to the air and are lost. With the corn popper described, wherein the popping kettle is a closed kettle, the volatile oils do not escape to the atmosphere but are retained in the kettle and reabsorbed into the popped corn; thus greatly adding to the pleasant flavor of the corn. The increased volume 45 of the popped corn is evidenced by the fact that an ordinary cupful of unpopped corn, when popped, will fill a ten quart kettle. The lard or other grease is so thoroughly 50 reabsorbed that it will give no evidence of its presence when the corn is placed in paper bags, which is the usual method of packing, such paper bags or other receptacles being 55 readily stored, temporarily, on that portion 60 65

of the table or cover provided with the railing 40.

What is claimed is:—

1. In a corn popper, a cabinet with a burner-containing portion at the top, and having a space at the top adjoining the burner-containing portion, said space adapted to receive a pan for popped corn, and a cover for the cabinet movable to uncover the top of the cabinet to obtain access to said burner-containing portion and said space and provided with a railing of a size, shape and position to house in the burner-containing portion of the cabinet when the cover is closed. 70 75

2. In a corn popper, a cabinet with a burner-containing portion at the top, and a cover hinged to the end of the cabinet remote from the burner-containing portion, and provided with a railing at the end of the cover remote from the hinged end, for supporting packages of popped corn, said railing being located on the inner face of the cover and having a size and shape and being in position to house in that part of the cabinet containing the burner when the cover is closed. 80 85 90

3. A corn popper structure including a cabinet, a burner therein, a jacket for the burner, a popping kettle, and a support for the kettle carried by the jacket and arranged within the latter, said support comprising a ring of a size to support the kettle in operative relation to the burner and depending within the jacket, and brackets supporting and spacing the ring from the jacket in interior concentric relation thereto. 95 100

4. A corn popper comprising a cabinet with a burner therein, a casing for the burner, a popping kettle depending within the casing, a support in the casing for the kettle, and a windshield encircling the kettle when on the support and extending within the casing, and expansible to embrace and slip over the outside of the casing for storage purposes. 105 110

5. A corn popper comprising a cabinet with a burner therein, a casing surrounding the burner, a popping kettle, a support for the kettle carried by the casing, and a windshield for encircling the kettle when on the support and extending within the casing so as to rest upon the support, and comprising a cylindrical member having its circumferential continuity broken and thereby expansible to embrace and slip over the outside of the casing for storage. 115 120

6. A corn popper structure including a cabinet, a burner therein, a casing for the burner, a popping kettle, and a support for the kettle carried by the casing and arranged within the latter, said support comprising a ring of a size to support the kettle in operative relation to the burner and depending within the casing, brackets sup- 125 130

porting and spacing the ring from the casing in interior concentric relation thereto, and a windshield encircling the kettle when on the support and resting upon said brackets.

7. A corn popper comprising a cabinet with a burner therein, a casing for the burner, a popping kettle depending within the casing, a support in the casing for the 10 kettle, and a windshield encircling the kettle when on the support, said windshield resting on said support and extending above the top of the casing and also above the top of the cabinet.
15. 8. A corn popper comprising a cabinet with a burner therein, a casing for the burner, a popping kettle, a support in the casing for the kettle, and a windshield of less diameter than the casing supported 20 within the latter around that portion of the kettle which depends within the casing, said windshield extending above the top of the casing and also above the top of the cabinet.

9. In a corn popper, a pan of a size to 25 store a kettle when not in use and provided with a recess for passing the handle of the kettle, and a cover for the recess movable into and out of closing relation to said recess, whereby the recess may be opened to 30 permit the passage of the kettle handle when placing the kettle in the pan, and said recess may be closed to complete the continuity of the pan when the kettle is removed.

10. In a corn popper, a cabinet having a 35 platform, a pan having an open top supported from the top of the cabinet and reaching close to the platform, a casing supported on said platform at one side of the pan and extending to the top of the cabinet, 40 a burner within the casing, a support for a kettle mounted above the burner within the casing, but not projecting above the latter, said casing and said pan not projecting above the top of the cabinet, and a cover

for closing the entire top of the cabinet including the pan and casing. 45

11. A corn popper comprising a cabinet, a support for a kettle located at one end of the cabinet, and a pan located at the other end of the cabinet, said pan having 50 an open top being of a size to house and contain the kettle when the latter is not in use.

12. A corn popper comprising a cabinet, and a pan located at one end of the cabinet, 55 within the same and having its top opening out at the top of the cabinet, and a hinged cover for the cabinet for closing the pan and movable to an open position at one side of the pan and then constituting a working 60 table in substantially the same horizontal plane as the top of the cabinet, said corn popper being provided with supporting means including wheels, and a propelling 65 handle movable into and out of the cabinet and when extended constituting a support for the open cover.

13. A corn popper comprising a vehicle including a cabinet, a burner and kettle support within the cabinet, a hinged cover for the cabinet for overlying the burner and movable to an open position at one side of the cabinet to constitute a work table, said cover having a railing which is housed within the burner portion of the cabinet when the cover is closed, and propelling handles for the cabinet, said handles telescoping into the cabinet for storage purposes and when projected constituting a support for the open cover. 70

In testimony, that I claim the foregoing 75 as my own, I have hereto affixed my signature.
